TIE PLATE INTERLOCKING TWO-WAY
RAIL ANCHORPerry H. Hamilton, Baltimore, Md., assignor, by
mesne assignments, to Poor & Company, Chi-
cago, Ill., a corporation of Delaware

Application May 21, 1942, Serial No. 443,850

10 Claims. (Cl. 238—315)

This invention relates to an improved rail anchor adapted to grip the base portion of a railroad rail and to also have a cooperative holding engagement with an adjacent tie plate on which the rail is supported.

One of the principal objects of the invention is the provision of a two-way rail anchor device formed to grip one flange only of a rail and adapted to so engage the forward and rear edges of the tie plate as to resist creeping movement of the rail in both forward and reverse directions and at the same time maintain the rail anchor device in its operative rail-gripping position.

Another object is to provide a rail anchor device of the above character having under-rail portions adjacent the forward and rear edges of the tie plate, which under-rail portions are adapted to flex lengthwise of the rail during the application of the anchor device to its applied position, the rail gripping jaws being formed to exert on the said under-rail portion increasing stresses, during the applying movement of the anchor, which increases the clasping action of the anchor on the edges of the tie plate.

A further and more specific object of the invention is to provide a two-way anchor device which is so formed and engaged with an adjacent tie-plate on which the rail is supported that the anchor device can be formed with less metal than has been required for devices of this general character and which at the same time will permit vertical movement of the rail relative to the tie plate, when the rail is subjected to vertical flexing or wave movement incident to the passing of a train over the track.

The invention is illustrated in two specific embodiments in the accompanying drawings, wherein

Fig. 1 is a fragmentary view in vertical section taken through a railroad rail looking toward a tie-plate and rail supporting structure and illustrating a side view of the improved rail anchor device of the present invention.

Fig. 2 is a plan view of the several elements indicated in Fig. 1 showing the lower jaws of the improved rail anchor device formed to provide spaced bearing surfaces for resiliently gripping the forward and rear edge portions of a tie-plate at spaced locations.

Fig. 3 is a fragmentary plan view showing the anchor device and the tie plate interlocked with each other, said interlocking engagement resulting from grooves worn in the edges of the tie plate by the vertical rubbing movement of V-

shaped end portions of the anchor device against the said edges of the plate.

Fig. 4 is a view looking at the side of a railroad rail and illustrating a manner in which the improved rail-gripping device extends into the spaces between the bottom surface of the rail base and the top surface of the tie at opposite edge portions of the tie-plate, and

Fig. 5 is a view similar to Fig. 2 illustrating a similar rail anchor device in which the lower jaws are formed to bear throughout their full length against the forward and rear edges of the tie-plate.

Referring first to Figs. 1, 2 and 4 of the drawings: 10 designates the base portion of a railroad rail, 11 one of the railway cross-ties, 12 is a tie-plate interposed between the base flange of the rail and the top surface of the cross-tie and 13 is a two-way rail anchor device constructed according to this invention.

The tie-plate may be any of the well known constructions and may be of any suitable width. For the purpose of illustration, the plate herein shown is formed with rail abutting ribs 14—14 positioned at opposite sides of a rail seat 15 and is of less width than the cross-tie 11. The plate may be secured to the cross-tie by any suitable means, for example, by spikes 16 which are driven through openings 17 of the tie plate and into the underlying cross-tie.

The rail anchor device 13 comprises a metal bar bent at opposite ends to form similar U-shaped ends which extend transversely of the bar and provide rail gripping jaws 18—19 and 18a—19a which grip the top and bottom surfaces, respectively, of one base flange only of the rail at locations adjacent the forward and rear edges of the tie-plate. The upper jaws 18—18a are formed to bear on the top inclined surface of the rail flange only at a substantial distance inwardly from the edge of the flange and are connected by a portion 20 of the bar which extends lengthwise of the rail. The said portion 20 is bowed upwardly for a portion of its length relative to the rail, as indicated at 21, so as to provide a clearance between the top surface of the rail base and the intermediate portion 21 of the bar 20. This construction, together with the curving of the upper jaws at 22—22a (Figs. 2, 4 and 5), confines the grip of the upper jaws to the surfaces 23—23a (Fig. 4). These surfaces are positioned inwardly from the vertical planes of the lower jaws 19—19a, that is to say, the surfaces 23—23a are spaced apart lengthwise of the rail 55 a less distance than the rail-gripping surfaces

of the lower jaws. The said upper jaws are also spaced vertically from the lower jaws a distance less than the vertical thickness of the rail base flange. Consequently the upper and lower jaws are spread apart slightly when the anchor is driven onto the rail flange. By reason of the offset relation of the upper and lower jaws, the upward pressure on the surfaces 23-23a during their movement upwardly on said inclined top surface of the rail flange, tends to turn or cant the U-shaped jaw portions about horizontal axes extending transversely of the rail and thereby presses the lower jaws 19-19a, particularly that portion thereof adjacent the edges of the rail, into increased clamping engagement with the 15 forward and rear edge portions of the tie-plate.

In addition to the above resilient clamping action exerted by the jaws 19-19a on the tie plate by reason of the turning movement of the jaws, the ends of the lower jaws are preferably spaced apart a distance less than the width of the tie plate so that it is normally necessary to flex the outer ends of the lower jaws apart when forcing the anchor to its applied position. The reflex of the said lower jaws force their outer end portions into firm resilient grip with the forward and rear edges, respectively, of the tie plate.

The said outer ends of said lower jaws are preferably turned outwardly, as shown at 24-24a, to provide cam surfaces 25-25a which ride over the edges of the tie-plate and assist in spreading the lower jaws apart during the initial applying movement of the device to a rail. The said jaws are also preferably bowed lengthwise of the rail, so that they will engage the tie-plate only at spaced locations 27-27a transversely of the rail.

The V-shaped ends 27a of said lower jaws have vertical rubbing engagement with the edges of the tie-plate, during the movement of the rail relative to the tie-plate. The said vertical rubbing movements, when continued for a sufficient length of time, form grooves in the forward and rear edges of the tie plate, such as indicated at 28 in Fig. 3, and thereby effect interlocking engagement of the anchor device and the tie plate.

In applying the anchor to its operative position on the rail, the cam surfaces 25-25a of the angular ends 24-24a are first forced over opposite edges of the tie-plate, as shown in dotted position in Fig. 1. The anchor device is then lowered from the dotted line position to the horizontal position with a downward and outward turning movement. At the same time the lower jaws are forced along the front and rear edges of the tie-plate beneath the rail base. Engagement of the upper jaws on the inclined face of the rail base flange tends to press the lower jaws into firm spring gripping engagement with the bottom surface of the rail base. The offset relation of the upper jaws relative to the lower jaws exert a turning movement on the jaw portions tending to increase the resilient clamping action of the lower jaws on the front and rear edge portions of the tie plate. When the anchor has been driven to its final position, the V-shaped portions 27a of the lower jaws, together with the bearing surfaces 27-27 exert a resilient clamping action on the tie plate to prevent the rail anchor device from backing off the rail.

Referring now to the embodiment shown in Fig. 5: The anchor device shown in this figure is the same as the previous device except that the lower jaws designated 30 in this figure are not bowed lengthwise of the rail, as shown in the

previous embodiment. The said lower jaws 30, therefore, bear throughout their length against the opposite edges of the tie-plate. In other respects, the modified anchor device may be, and preferably is, the same as previously described in connection with Figs. 1 to 4 inclusive.

While this invention is illustrated in two specific embodiments it will be obvious to those familiar with the art that other modifications in structure might be made without material departure from the terms or spirit of the invention described herein.

I claim:

1. A rail anchor for resisting longitudinal creeping of a railroad rail in either direction comprising a bar bent at opposite ends to form U-shaped portions extending transversely of the bar and defining upper and lower jaws adapted to be driven into spring gripping engagement with the top and bottom surfaces of a rail base flange and to abut against the forward and rear faces of a rail supporting structure, the said upper and lower jaws being arranged out of vertical alignment with each other, whereby the applying movement of said upper jaws on the inclined surface of a rail base flange tends to move the lower jaws toward said supporting structure and exerts a resilient clamping action of said lower jaws on the said forward and rear faces of the said supporting structure.

2. A rail anchor for resisting longitudinal creeping of a railrod rail in either direction comprising a bar bent at opposite ends to form U-shaped portions extending transversely of the bar and defining upper and lower jaws adapted to be driven into spring gripping engagement with the top and bottom surfaces of a rail base flange and to abut against the forward and rear faces of a tie plate on which the rail is supported, the length of the lower jaws being less than the width of the rail base and the upper and lower jaws being arranged out of vertical alignment with each other whereby the applying movement of said upper jaws on the inclined surface of a rail base flange tends to move the lower jaws toward said supporting structure and exert a resilient clamping action of said lower jaws on the said forward and rear faces of the rail supporting structure.

3. A rail anchor for resisting longitudinal creeping movement of a railroad rail in either direction comprising a bar bent at opposite ends to form U-shaped portions extending transversely of the bar and defining upper and lower jaws adapted to be driven into spring gripping engagement with the top and bottom surfaces of a rail base flange and to abut against the forward and rear faces of a tie plate on which the rail is supported, the lower jaws being of a length less than the width of the base portion of the rail and having a resilient clamping engagement with the said forward and rear edge portions of the plate to hold the device from backing off the rail.

4. A rail anchor for resisting longitudinal creeping of a railroad rail in either direction comprising a bar bent at opposite ends to form U-shaped portions extending transversely of the bar and defining upper and lower jaws adapted to be driven into spring gripping engagement with the top and bottom surfaces of a rail base flange and to abut against the forward and rear edge portions of a tie plate on which the rail is supported, the lower jaws being bowed lengthwise of the rail to provide tie-plate engaging surfaces

spaced apart transversely of the rail and the said jaws being normally positioned, whereby it is necessary to spread them apart to apply them over the opposite edges of the tie plate and whereby reflex of said jaws exerts a strong spring grip on said forward and rear edge portions of the tie plate to hold the device from backing off the rail.

5. A rail anchor for resisting longitudinal creeping of a railroad rail in either direction comprising a bar bent at opposite ends to form U-shaped portions extending transversely of the bar and defining upper and lower jaws adapted to be driven into spring gripping engagement with the top and bottom surfaces of a rail base flange and to abut against the forward and rear edge portions of a tie plate on which the rail is supported, the lower jaws being of a length less than the width of the base portion of the rail and normally spaced apart a distance less than the width of the tie plate, whereby it is necessary to spread them apart to apply them over the opposite edges of the tie plate and whereby the reflex of said jaws exerts a strong gripping action on the forward and rear edge portions of the tie plate, and the said upper and lower jaws being arranged out of vertical alignment with each other, whereby the applying movement of the upper jaws on the inclined surface of the rail base flange so tensions the anchor as to increase the resilient clamping engagement of said lower jaws on the tie plate.

6. A rail anchor for resisting longitudinal creeping of a railroad rail in either direction comprising a bar intermediately bowed upwardly and provided at opposite ends with U-shaped portions defining upper and lower jaws adapted to be driven transversely of a rail into spring clamping engagement with the top and bottom surfaces of the rail base flange, and the lower jaws being of lengths less than the width of the rail base and flexed apart lengthwise of the rail into spring clamping engagement with the forward and rear edge portions of the tie plate.

7. A rail anchor for resisting longitudinal creeping of a railroad rail in either direction comprising a bar provided at opposite ends with U-shaped portions defining upper and lower jaws adapted to be driven transversely of a rail into spring clamping engagement with the top and bottom surfaces of the rail base flange; the lower jaws being of lengths less than the width of the

rail base and positioned to bear throughout their length with a resilient clamping pressure against the forward and rear edges of the tie plate to hold the anchor device on the rail.

5. In combination with a tie plate having a notch in a vertical edge thereof and interposed between a railroad rail and an underlying cross-tie with the notched edge of the plate extending transversely of the rail, of a rail clamping device formed with pairs of upper and lower spring jaws spaced apart for gripping one flange only of a rail base at locations adjacent the forward and rear edge portions of the plate, the length of said lower jaws being less than the width of the rail base and one of said lower jaws being formed with a portion extending into said notch of the plate to provide an interlocking engagement therewith.

9. In combination with a tie plate interposed between the railroad rail and an underlying cross-tie and having a notch in each of its forward and rear edges, of a rail clamping device formed with pairs of upper and lower jaw portions adapted to grip the top and bottom surfaces of a rail base flange with spring pressure at locations adjacent the forward and rear edge portions of said tie plate, the ends of said lower jaws being normally spaced apart a distance less than the width of the tie plate and formed with angularly disposed portions providing cam surfaces adapted to engage the opposite edges of the tie plate to force said lower jaws apart during the initial applying movement of the clamp device and provided also with means fitting in said notches to form an interlocking engagement.

10. In combination with a tie plate having notched forward and rear edges and interposed between the base portion of a rail and an underlying cross-tie, of a one-piece rail clamping device for gripping one flange only of the rail base comprising a bar formed at opposite ends with U-shaped portions defining upper and lower resilient jaws adapted to be driven transversely of the rail into spring gripping engagement with the top and bottom surfaces of said base flange and the said lower jaws being flexed apart lengthwise of the rail and having means held by the reflex pressure of said lower jaws in interlocking engagement with said notches.

PERRY H. HAMILTON.
